UNITED STATES PATENT OFFICE.

ARTHUR E. SMALL, OF CHICAGO, ILLINOIS.

SPACER FOR REINFORCING ELEMENTS OF CONCRETE STRUCTURES.

1,356,021.

Specification of Letters Patent.

Patented Oct. 19, 1920.

Application filed May 8, 1920. Serial No. 379,919.

To all whom it may concern:

Be it known that I, ARTHUR E. SMALL, a citizen of the United States, residing at Chicago, in the county of Cook and State of Illinois, have invented new and useful Improvements in Spacers for Reinforcing Elements of Concrete Structures, of which the following is a specification.

This invention relates to the art of reinforced concrete building construction, and more particularly to devices for spacing the reinforcing elements from each other and from the mold while the concrete is being put in the mold.

15 The invention has for its object to provide a very simple, inexpensive and efficient spacing device of the kind stated, and to this end it consists in a novel combination and arrangement of parts to be hereinafter described and claimed.

In order that the invention may be better understood, reference is had to the accompanying drawing forming a part of this specification, and in said drawing,

25 Figure 1 is a front elevation of one of the devices;

Fig. 2 is a side elevation thereof;

Fig. 3 is a detail in perspective;

30 Fig. 4 is a plan view of a fragment of a blank out of which the devices are made, and

Fig. 5 is a cross section of a mold showing the manner in which the devices are used.

35 Referring specifically to the drawing, 10 denotes the fragment of a mold for forming a reinforced concrete beam or other building element. In the mold are placed reinforcing members such as rods 11, and 40 these members are held spaced from each other and from the mold while the concrete is being put in the latter, by the devices which are the subject matter of the present application for patent.

45 Close to the bottom of the mold 10 is placed a transverse bar 12 which is supported by a number of chairs having seats for the rods 11. Each chair is a plate which is angular in cross-section to form a web 13 and outstanding end flanges 14, said flanges projecting in opposite directions. The bar 12 has apertures 15 at regular intervals through which the chair members are stuck to project from the top and also from the 55 bottom of the bar. The chair members are thus held spaced, and they seat on the bot-

tom of the mold as shown in Fig. 5, to hold the bar 12 in place within the mold and spaced from the bottom thereof. The oppositely projecting end flanges 14 prevent the chair members from tipping over, and said members are thus held standing in upright position.

The rods 11 are laid on the top edges of the webs 13 of the chair members, and said edges are made slightly concave to provide a better seat for the rods. Tie wires 16 are employed for anchoring the rods to the chair members, said wires being passed through apertures 17 in the webs 13 and 70 around the rods, with the ends of the wires united by being twisted together as shown in Figs. 1, 2 and 5. The rods 11 are thus firmly tied to the chair members so that their position is not disturbed when the concrete is 75 put in the mold.

The aperture 17 is produced by cutting or punching a tongue 18 from the web, and this tongue is bent to extend laterally therefrom and seat on top of the bar 12.

80 It will be noted that the flanges 14 have their outer edges stepped to produce shoulders 19 on top of which the bar 12 seats, said shoulders therefore preventing the bar from slipping down on the chair member, and serving to hold the bar spaced from the base of the chair member to obtain the proper spacing from the mold bottom. The outer edges of the flanges 14 are also inclined so that they are wider at the bottom than at 90 the top to obtain greater stability.

The chair members can be cut from a long sheet metal strip so that there is no waste of material, Fig. 4 of the drawing illustrating a fragment of this strip. The devices can therefore be cheaply produced.

I claim:

1. A device of the character described comprising an apertured bar, a chair member seating in the aperture of the bar and projecting from opposite sides thereof, the edge of one of the projecting portions of the chair member having a seat to support a reinforcing element, and said projecting portion below said seat having an aperture 100 to seat a tie wire, and the other projecting portion forming the supporting base of the chair member.

2. A device of the character described comprising an apertured bar, a chair member seating in the aperture of the bar and projecting from opposite sides thereof, the 110

edge of one of the projecting portions of the chair member having a seat to support a reinforcing element, and said projecting portion having an outstanding abutment 5 seating on the bar, and the other projecting portion forming the supporting base of the chair member, said chair member having shouldered side edges forming seats for the aforesaid bar.

10 3. A device of the character described comprising an apertured bar, a chair member seating in the aperture of the bar and composed of a web and outstanding flanges at the ends thereof, said chair member projecting from opposite sides of the bar, the edge of one of the projecting portions of the chair member having a seat to support a reinforcing element, and the other projecting portion forming the supporting base of 15 the chair member.

15 4. A device of the character described comprising an apertured bar, a chair member seating in the aperture of the bar and composed of a web and outstanding flanges 20

at the ends thereof, said chair member projecting from opposite sides of the bar, the edge of one of the projecting portions of the chair member having a seat to support a reinforcing element, and the other projecting portion forming the supporting base of 25 the chair member, the extremities of the aforesaid flanges being shouldered to form 30 seats for the bar.

5. A device of the character described comprising an apertured bar, a chair member seating in the aperture of the bar and composed of a web and outstanding flanges 35 at the ends thereof, said chair member projecting from opposite sides of the bar, the edge of one of the projecting portions of the chair member having a seat to support a reinforcing element, and provided with an aperture below said seat to receive a tie 40 wire, and the other projecting portion forming the supporting base of the chair member. 45

In testimony whereof I affix my signature.
ARTHUR E. SMALL.
